COMBINED DASHBOARD AND STEERING WHEEL FOR AN AUTOMOBILE

Jean Cadiou, 36 Rue Daily, Saint Cloud, France

Continuation-in-part of abandoned design application Ser. No. 25,787, Nov. 2, 1970. This application Oct. 31, 1972, Ser. No. 302,547

Claims priority, application France May 6, 1970

Term of patent 14 years

Int. Cl. D12—16

U.S. Cl. D12—192

FIG. 1

FIG. 2

FIG. 3

FIG. 4

FIG. 5

FIG. 6

FIG. 1 is a front elevational view of a combined dashboard and steering wheel for an automobile showing my new design;

FIG. 2 is a top plan view thereof;

FIG. 3 is a left side elevational view thereof;

FIG. 4 is a right side elevational view thereof;

FIG. 5 is a rear elevational view thereof; and

FIG. 6 is a bottom plan view thereof.

This is a continuation-in-part of design application Ser. No. D. 25,787, filed on Nov. 2, 1970 and now abandoned.

I claim:

The ornamental design for a combined dashboard and steering wheel for an automobile, as shown and described.
